UNITED STATES PATENT OFFICE.

WILLIAM DENEKE, OF COVINGTON, KENTUCKY.

STRETCHER AND CASKET SUPPORT.

1,268,938.

Specification of Letters Patent. Patented June 11, 1918.

Application filed January 7, 1918. Serial No. 210,646.

To all whom it may concern:

Be it known that I, WILLIAM DENEKE, a citizen of the United States of America, and resident of Covington, in the county of Kenton and State of Kentucky, have invented a new and useful Improvement in Stretcher and Casket Supports, of which the following is a specification.

An object of my invention is to produce an improved support adapted to aid in supporting stretchers or caskets while placing them in ambulances or hearses, and adapted thereby to relieve the bearers of the entering end of the stretcher or casket, of a great proportion of the inconvenient and awkward lifting usually necessary to accomplish the placing of the stretcher or casket within the vehicle.

This and other objects are attained in the support described in the following specification and illustrated in the accompanying drawing, in which:

Figure 1 is a perspective view of a portion of an ambulance having a support embodying my invention, located thereon, the position of a stretcher with relation thereto, being shown in dotted lines.

Fig. 2 is a fragmental sectional perspective view of a support embodying my invention.

Fig. 3 is a sectional view taken on the line 3—3 of Fig. 1.

Fig. 4 is a perspective view of a detail of my invention.

My improved support consists of an arm 5 slidably mounted in a way 6 formed in a casing 7 adapted to be built into the side of the vehicle as shown in Fig. 1, and a supporting hook 8 suitably mounted in the arm.

Arm 5 preferably is provided with rollers 9, 10 and 11 so that its movement within way 6 will be free. In addition to this a roller 12 is mounted in casing 7 at the bottom of way 6 and adjacent to its outer end, as shown in Fig. 2, for assisting in this freedom of movement of the arm.

At the outer end of arm 5 the supporting hook 8 is located and a raising and lowering mechanism is located on the upper surface of the arm. Upon the inner face of the arm a spring 20 is secured, having its end bearing against the hook to move it to the dotted line position shown in Fig. 3, when the hook is dropped. Bell crank 17 is arranged to retain the hook in elevated position by having its short arm 16 adapted to

be thrown off center to bring the handle into bearing engagement with the arm as shown in full lines in Fig. 3. As soon as the handle is moved to the dotted line position shown in Fig. 3, link 15 and hook 13 are dropped, spring 20 moving the hook to dotted line position when the upper end thereof passes shoulder 21 in passage 14.

In using my improved support it is but necessary to move handle 18 to the full line position shown in Fig. 3, to pull arm 5 out to its fullest extent and to then place the adjacent stretcher bar into the hook as the front stretcher bearer arrives at the ambulance, as shown in Fig. 1. While supporting the opposite side of the stretcher the stretcher bearers push the stretcher into the ambulance and when the entering end is well into the ambulance, with bracket 19 in engagement with the end of casing 7, handle 18 is moved to dotted line position and hook 13 is thereby dropped and moved from engagement with the stretcher. The stretcher now being free may be pushed into the ambulance until it rests entirely upon the floor thereof.

My support is equally serviceable for use in hearses in supporting one side of one end of a casket while it is being placed in the hearse and when there are but two persons available for carrying the casket. For this purpose I have provided a supporting plate 22, see Fig. 4, which has an extension 23 adapted to occupy passage 14, and a link 24 adapted to occupy the position of link 15 and to be detachably connected with bell crank 17 as by a thumb nut and bolt 25 which is shown in Fig. 3 as detachably connecting link 15 with bell crank 17. The upper surface of plate 22 is roughened to prevent slippage of the casket from the plate while the casket is being pushed into the hearse.

To use the plate it is but necessary to detach the hook link 15 from bell crank 17, and after removing the hook, to place link 24 and extension 23 in position and then connect the plate link 24 to bell crank 17 by means of thumb nut and bolt connection 25. The casket is then brought to position with one corner upon the plate and while being supported by a person upon its opposite side, it is pushed into the hearse, the arm moving in to collapsed position with relation to its casing. As soon as in collapsed position, the plate is lowered to bring the

end of the casket to rest upon the hearse floor, after which it is pushed to position within the hearse.

Having thus described my invention, 5 what I claim is:

1. A stretcher support comprising a casing located in the side of a vehicle, an arm reciprocally mounted in the casing, and means on the end of the arm adapted to support a stretcher.
2. A stretcher support comprising a casing located in the side of a vehicle, an arm reciprocally mounted in the casing, means on the end of the arm adapted to support a stretcher, and means adapted to release the stretcher from the support.

3. A stretcher support comprising a casing located in the side of a vehicle, an arm reciprocally mounted in the casing, a hook located at the end of the arm, and means adapted to raise the hook to receive a stretcher when the arm is in the withdrawn position and adapted to lower the hook to release the stretcher when the arm is retracted into the casing.

In testimony whereof, I have hereunto subscribed my name this 4th day of January, 1918.

WILLIAM DENEKE.
